LOCK

Filed June 20, 1928

Fig. 2.

UNITED STATES PATENT OFFICE

ELLSWORTH F. SEAMAN, OF BIRMINGHAM, ALABAMA

LOCK

Application filed June 20, 1928. Serial No. 286,785.

This invention relates to locks, and is more particularly concerned with portable locks of the "pad-lock" type in which a shackling element is inserted through an opening and is held locked against unauthorized removal.

An object of the present invention is the provision of a portable lock of this type having a shackling element formed for general application and use and presenting an abutment surface of substantial area resisting withdrawal.

A further object is the provision of a lock having a shackling element capable of insertion through locking openings with the shackling element and the body of the lock capable of assuming different angular positions. Such an arrangement disposes the body of the lock where it is out of the way and does not present an obstruction or an awkward appearance.

The invention consists in the constructions, arrangements and combinations hereinafter described and claimed and is more fully described in the following detailed specification which is to be read in conjunction with the accompanying drawings forming part thereof and in which:—

Figure 1 is a perspective view of a lock constructed in accordance with the present invention, the toggle shackle being shown in flexed locked position.

Figure 2 is a side elevation of the lock shown in Figure 1.

Figure 3 is an end elevation of said lock with the shackle inserted through a fastener opening and flexed to locking position and with the main lock body angularly disposed relatively to the shackle and its supporting yoke.

Figure 4 is a vertical sectional view through the lock in toggle flexed position, taken on line 4—4 of Figure 2, the links of the toggle being shown in dotted lines in their straightened longitudinally aligned position for insertion through a fastener opening.

Figure 5 is a transverse horizontal section taken on line 5—5 of Figure 4.

Figure 6 is a fragmentary detail showing the key-receiving locking foot of the actuating plunger.

Figure 7 is an exploded view of the toggle links and their actuator plunger.

Figure 8 is a detail of a key such as may be used to operate the plunger.

In structurally embodying the invention, provision is made of a main lock body portion 1 of suitable shape and material which is cored to provide a central circular bore 2 extending vertically therethrough. The base of body 1 may be faced by a plate 3 having its inner face in line with bore 2 provided with a circular recess of greater diameter than the bore seating a key hole disk 4 having its edges held between plate 3 and body 1 for rotative movement.

The upper face of the body portion 1 in line with the bore 2 is formed with an upstanding anchor block 5 centrally bored in alignment with the bore 2 which extends upwardly within the anchor block. At opposite sides of this bore, parallel upstanding wings 6 are provided. Between these wings and the opposite outer faces of the anchor block, curved seats 7 are formed to receive the similarly curved feet 8 of an elongated shackle yoke 9, the parallel vertical bars 10 of which are joined at their upper ends by the cross bar 11 forming an abutment seat for a shackle in the form of a toggle joint mounted within the yoke between its bars 10. This toggle joint is formed of complementary pairs of pivotally interconnected links, the upper links 12 of each pair being provided with staggered hinge lugs 13 (Figure 7) by means of which they are pivotally connected to each other and to the upper end of the yoke through a pivot pin 14. The lower ends of the upper links 12 and the upper ends of the lower links 15 of each pair have similarly arranged hinge lugs by means of which they are interconnected through pivot pins 16. The lower free ends of the pairs of interconnected links 12 and 15 have similar hinge lugs 17 by means of which they are pivoted to the ear 18, Figure 7, at the upper end of an actuating plunger 19 which extends through the bore in the anchor block 5 which bore is aligned with the pivot point 14 at the upper end of the yoke. The actuating plunger 19 is provided with an oper-

ating lower section 20 (Figure 4) to which it is pivotally connected at 21 to aline with the points of pivotal connection of the lower ends of the yoke bars 10 with the anchor block 5 when the plunger 19 is in fully outdrawn position as will be later described.

The lower section 20 of the actuating plunger is housed within the bore 2 at all times, and is constructed to be normally positioned at the lower end of the bore 2 and arranged for reverse movement through key controlled means to actuate the locking toggle joint to a fastener locking position.

Accordingly, the bore 2 is provided with diametrically opposite slots 22 therein extending from the bottom plate 3 upwardly to a point adjacent the top face of the block where they are merged into an annular recess 23 forming retaining ledges extending outwardly from the walls of the bore. The lower plunger section 20 is formed with a locking disk 24 having opposed radially extending arms 25. The diameter of the disk corresponds with that of the bore 2 and the radial arms 25 are of a length to extend in and slide up and down in the slots 22 and to enter and turn in the annular recess 23 and rest upon and be supported upon the ledges formed by the lower side thereof. Between the upper face of the disk 24 and the upper end of the anchor block 5 within the extension of the bore 2 therein, a coil spring 26 encircles the lower plunger section 20 and normally urges the plunger 19-20 downwardly when the arms 25 of its bottom disk are alined with and seat in the vertical slots 22. The disk 24 will, therefore, normally be positioned through the spring 26 at the bottom of the bore 2 in the main body 1. In this position, the toggle joint formed by the pairs of pivotally interconnected toggle links 12 and 15 will be straightened out so that the pairs of links 12-15 are in longitudinal alinement with each other and with the yoke bars 10. Therefore in this position of the parts, the yoke bars with the longitudinally alined toggle links may be easily inserted through a fastener opening such as the usual hasp eye. When the yoke and its toggle shackle have thus been inserted, a key, such as the key 27, (Figure 8) is inserted through the key disk 4 and into a correspondingly shaped slot 28 formed in the under side of the locking disk 24 of the actuating plunger 20, the slot extending only partway into the disk which is suitably swiveled on the plunger 20 for relative rotary movement. Upward pressure now applied to the disk through the inserted key will move the disk 24, and its connected plunger 19-20 upwardly until the arms 25 reach the upper ends of the slots 22. When this point is reached, the arms are alined with the annular recess 23 and the key is given a partial rotation bringing these arms over the lower wall of the recess

against which they are held by the pressure of the tensioned coil spring 26. As the key is thus rotated, the key disk 4 turns on the plate 3 and the swiveled connection of the disk 24 with the plunger 20 permits a similar rotating movement independently of the plunger. The key may now be withdrawn and the plunger is locked in its upwardly moved position.

This upward movement of the plunger flexes the toggle joints formed by the pairs of links 12-15 moving the links transversely, and in the construction shown, extending them in horizontal alinement to present a transversely extending abutment traversing a fastener opening such as the alined slots 29 in the fastener plates 30 (Figure 3) and preventing withdrawal of the shackle formed by the toggle joint from the fastener.

The extent of upward movement of the plunger 19 is pre-figured by reason of the location of the locking recess 23 to position the plunger pivot 21 in alinement with the point of pivotal connection between the lower ends of the yoke bars 10 and the anchor block 5. This alinement of points of pivotal connection in the locking position of the shackle toggle permits the toggle with its supporting yoke and upper plunger section 19 and the main lock body 1 with its anchor block 5 to have a relative angular swinging movement as suggested in Figure 3 so that the body of the lock will assume a vertical or other position at an angle to the yoke etc., and will not protrude from the fastener in line with the yoke to form an awkward obstruction. When it is desired to release the lock, the main body portion 1 will be swung upwardly to aline with the yoke, the key 27 will be inserted through the key disk 4 and into the slotted bottom disk 24 of the plunger and rotated to aline the arms 25 with the bore slots whereupon the coil spring 26 will function to move the plunger 19-20 downwardly straightening the links 12-15 of the toggle joint into longitudinal alinement as shown in dotted lines, Figure 4, and permitting the shackle formed by the toggle joint to be withdrawn through the fastener opening.

A lock constructed as above described has the advantage over padlocks as heretofore made or proposed in that its shackling element may be inserted through an appropriate opening in a door, drawer or other object to be locked, and through a hasp or other fastener located on the interior, so that with a lock of this type, a concealed hasp or other lock can be used which is not subject to breakage in attempted forcing of the locked part.

Preferably, the under face of the cross bar 11 of the yoke is oppositely beveled as at 31, Figure 4, to provide for engagement therewith of the upper ends of the links 12 in the flexed transversely extended position of

these links shown in Figures 1 and 4 so that the under face of the yoke cross bar provides an abutment resisting breaking of the toggle link through pressure against the transverse locking links 15 engaging with the fastener and bridging the fastener opening.

The lock construction, per se, forms, specifically, no part of the present invention and any suitable locking mechanism effective to provide for the closing and opening or alining and flexing of the toggle joint may be utilized. The specific construction of locking yoke, shackle, plunger and lock body, while representing a preferred embodiment 15 of the invention is intended as illustrative and not restrictive thereof, the construction being subject to modification and adaptation to suit varying conditions of manufacture and use within the spirit of the invention and 20 the scope of the appended claims.

What I claim therefore and desire to secure by Letters Patent is:—

1. A lock having a main body portion, jointed shackle links mounted externally thereon and extending outwardly therefrom and supported for movement from a normal position of longitudinal alinement permitting their insertion through a fastener opening to a transversely extended position traversing and opposing withdrawal from said opening, key controlled means for moving said links to and holding them in traversing locking position, and means mounting said links externally on said main body portion 35 constructed to permit relative angular movement between said main body portion and said mounting means in the transversely extending locking position of the links.

2. A lock having a body portion, a shackle 40 extending therefrom comprising a plurality of pivotally interconnected links pivotally supported at one free end from said body portion, an actuator mounted in and extending from said body portion and pivotally connected to the other free end of the plurality of interconnected links to move said links to and from a position of substantial longitudinal alinement permitting their insertion through a fastener opening to a flexed non-alining position presenting an abutment traversing the fastener opening and preventing withdrawal of the shackle therethrough, means normally tending to move said actuator to link alining position, and key controlled 55 means for moving said actuator to and from a link-flexing position locking said shackle in the fastener opening.

3. A lock having a main-body portion, a shackle yoke upstanding therefrom, a toggle joint shackle having its upper end pivotally attached to said yoke, an actuating plunger housed in said body portion and movable in line with said yoke, with its upper end pivotally connected to the lower end of said toggle joint, means normally tending to 60

move said plunger downwardly in said body portion to close said toggle joint to a position with its members in longitudinal alinement with each other and with said yoke to permit the insertion of the yoke and toggle through a fastener opening, and key controlled means for moving said plunger upwardly in said yoke to and holding it in a position expanding the toggle joint and transversely extending its members to provide an abutment traversing the fastener opening and locking the shackle against withdrawal therefrom.

4. A lock having a body portion, a shackle support extending upwardly therefrom and pivotally joined to said body portion at its lower end, a shackle comprising a pair of links pivotally interconnected and pivotally supported at their upper free end on said support, an actuator plunger mounted in said body portion for movement in the line of said support and having its upper end pivotally connected to the lower free end of the pair of links, means normally moving said plunger downwardly in said body portion to straighten said links into substantial longitudinal alinement with each other and with their support for insertion with their support through a fastener opening, and key controlled means for moving said plunger upwardly to and holding it in a position flexing said links to present a transverse abutment opposing withdrawal of the shackle links and their support from the fastener opening, with the point of pivotal connection of the plunger and links alined with the point of pivotal connection of said support and body portion.

5. A lock having a main body portion, a shackle yoke upstanding therefrom having its lower ends pivotally supported from and above said body portion, a toggle joint shackle having its upper end pivotally attached to said yoke, an actuating plunger housed in said body portion and movable in line with said yoke, with its upper end pivotally connected to the lower end of said toggle joint, means normally tending to move said plunger downwardly in said body portion to close said toggle joint to a position with its members in longitudinal alinement with each other and with said yoke to permit the insertion of the yoke and toggle through a fastener opening, and key controlled means for moving said plunger upwardly in said yoke to and holding it in a position expanding the toggle joint and transversely extending its members to provide an abutment traversing the fastener opening and locking the shackle against withdrawal therefrom, with the point of pivotal connection of plunger and toggle joint alined with the point of pivotal support of the yoke on said main body thereby to permit relative angular movement between said yoke and toggle and the main body portion.

6. A lock having a body portion and a toggle support exteriorly thereof and extended outwardly therefrom, a shackling toggle having one end pivoted to said support, an actuator connected to the other end of said toggle and extending in the plane of said support downwardly into said body portion and movable to position the toggle members substantially in longitudinal alinement with in the plane of said support for insertion with said support through an opening, and to flex said toggle members to extend transversely of the opening and the plane of said support and oppose removal of the shackle through said opening, means normally tending to move said actuator to toggle alining position, and key controlled means for moving said actuator to and locking it in toggle flexed position.
7. A lock having a main body portion, a shackle support on the exterior of said body portion, jointed shackle links permanently mounted on said support externally of the body portion and extending outwardly from said main body portion, an actuator connected with said links and extending into said body portion, means normally tending to move said links into positions of longitudinal alinement permitting their insertion through a fastener opening, and means for moving said actuator and links to and releasably holding them in a position with said links transversely extended to oppose their withdrawal through said opening.
8. A lock having a base, a toggle permanently mounted at one end externally on said base, an actuator connected to the other end of said toggle and extending into said base, means normally tending to move said toggle members to positions substantially in longitudinal alinement for insertion through a fastener opening, and key controlled means for moving said actuator and toggle to and releasably holding them in a position with said toggle flexed and traversing said opening to oppose withdrawal therethrough.
9. A lock having a main body portion, a shackling toggle permanently mounted at one end on the exterior of said body portion, an actuator connected to the other end of said toggle and extending into said body portion, means normally tending to straighten said toggle to position its members in substantially longitudinal alinement for insertion through a fastener opening, and key-controlled means on the interior of said body portion operable to move said actuator to flex said toggle and releasably to hold said actuator in toggle flexed position.
